PURGING DEVICE FOR CLOSED REFRIGERATION SYSTEMS

Edward M. Stubblefield, Evansville, Ind., assignor to Servel, Inc., New York, N. Y., a corporation of Delaware

Application January 8, 1952, Serial No. 265,418

9 Claims. (Cl. 62—119)

The present invention relates to refrigeration and more particularly to purging hydrogen from closed refrigeration systems.

The accumulation of non-condensable gases in closed refrigeration systems, and especially in vacuum type systems, has been a longstanding problem in the refrigeration art. Such gases usually comprise a high percentage of hydrogen, probably generated as a product of corrosion, and they blanket the heat transfer surfaces of the condenser and other parts such as the absorber in an absorption type system. In vacuum type systems the blanketing of the heat transfer surfaces is aggravated by the large volume of a small amount of hydrogen at the extremely low pressure in such a system. It has been the practice in vacuum type systems to continuously transfer non-condensable gases from the active parts of the system to a storage vessel in an inactive part of the system and to periodically remove the stored gases from the storage vessel.

One of the objects of the present invention is to provide an arrangement for automatically and continuously purging hydrogen from a closed refrigeration system to the atmosphere.

Another object is to provide a purging arrangement for a closed refrigeration system by which non-condensable gases are continuously transferred from other parts of the system to one of the elements thereof having a palladium wall through which hydrogen diffuses from a relatively high partial pressure in the system to a relatively low partial pressure in the atmosphere.

Another object is to provide a purging device for a closed refrigeration system in the form of a cell connected at its top and bottom to one element of the system and having a palladium tube extending vertically therethrough which is heated to increase the rate at which hydrogen diffuses through its wall.

Still another object is to provide a cell of the type indicated with automatically operated valve means to open the cell for communication with the refrigeration system when the latter is in operation and close the cell when the system is not in operation.

These and other objects will become more apparent from the following description and drawing in which like reference characters denote like parts throughout the several views. It is to be expressly understood, however, that the drawing is for the purpose of illustration only and not a definition of the limits of the invention, reference being had for this purpose to the appended claims. In the drawing:

Fig. 1 is a diagrammatic view of a vacuum type absorption refrigeration system showing the purging arrangement of the present invention applied thereto;

Fig. 2 is an enlarged sectional view of the purging cell or chamber connected at its top and bottom to the element to be purged and showing the palladium tube extending vertically through the chamber and the heating element for heating the cell; and

Fig. 3 is an enlarged view of a cell of modified con-

2

struction having valve means for automatically opening and closing communication between the cell and element to be purged.

While the purging device of the present invention may be applied to any closed refrigeration system, it is shown in the drawings applied to a vacuum type absorption refrigeration system which uses water as a refrigerant and a salt solution as an absorbent as described and claimed in the United States Letters Patent to C. A. 10 Roswell Reissue 23,093 issued March 22, 1949. The absorption refrigeration system as illustrated in Fig. 1 comprises a generator 5, a condenser 6, an evaporator 7, an absorber 8 and heat exchanger 9 interconnected to provide a closed circuit. In the illustrated embodiment the generator 5 has a series of upright tubes 10 connected at their lower ends to an inlet chamber 11 for absorption solution and connected at their upper ends to a separating chamber 12. Surrounding the tubes 10 is a shell 13 providing a heating chamber 14 therebetween.

Steam supplied to the heating chamber 14 from any suitable source transfers heat through the tubes 10 to the absorption solution therein to expel refrigerant vapor therefrom. The refrigerant vapor rises upwardly 25 through the tubes 10 at considerable velocity and raises absorption solution at the sides of the tubes by a climbing film action. The refrigerant vapor flows from the separating chamber 12 to the condenser 6 through a conduit 15 and liquefied refrigerant flows by gravity from 30 the condenser through an orifice device 16 and conduit 17 to the evaporator or cooling element 7. The orifice device 16 comprises a closed chamber 18 having an orifice 19 therein as described and claimed in the United States Letters Patent to N. E. Berry 2,563,575 issued 35 August 7, 1951. The orifice 19 is of such dimensions as to permit the concurrent flow of liquid refrigerant and non-condensable gases with refrigerant vapor while maintaining a difference in pressure corresponding to the vapor pressures in the condenser 6 and evaporator 7, 40 respectively. Evaporator 7 comprises a plurality of substantially horizontal tubes 20 arranged one over the other and extending between headers 21 and 22 with connecting means in the headers between adjacent tubes alternately at opposite ends. Liquid refrigerant supplied to the uppermost tube 20 flows by gravity through 45 each of the tubes successively from the top to the bottom of the evaporator and refrigerant vapor flows from the tubes and through the headers 21 and 22 to the absorber 8.

Absorption solution weak in refrigerant, or, in other words, a concentrated salt solution, flows by gravity from the separating chamber 12 to the top of the absorber 8 in a path of flow including the conduit 23, outer passages 24 of the liquid heat exchanger 9 and conduit 25. It will be understood that the bottom of the separating chamber 12 is located above the upper end of conduit 25 where it enters the absorber 8 to initially cause solution to flow to the absorber by gravity. The solution in the absorber 8 absorbs the refrigerant vapor and this solution strong in refrigerant or, in other words, dilute salt solution, flows by gravity from the bottom of the absorber 8 to the inlet chamber 11 at the lower end of generator 5 in a path of flow including conduit 26, inner passages 27 of liquid heat exchanger 9, conduit 28, leveling vessel 29 and conduit 30 to complete the cycle. The absorption of refrigerant vapor in the absorber 8 causes refrigerant to evaporate in the evaporator 7 at a low pressure and temperature to produce a refrigerating effect and the low pressure in the evaporator and absorber is maintained by liquid columns in the conduits 25 and 26. After the refrigeration system has been in operation for a short period of time a column

of liquid will stand in conduit 26 between the levels X and Y and a liquid column will stand in the conduit 25 between the levels Z and the top of the conduit which balance the difference in pressure between the high and low pressure sides of the system.

The absorber 8 and condenser 6 are cooled by cooling water from any suitable source which flows through the elements successively. The cooling water is delivered to a plurality of cooling coils 31 in the absorber 8 from a conduit 32 and header 33 connecting one end of the coils. The outlet ends of the cooling coils 31 are connected together by a header 34 and the cooling water from the absorber flows through conduit 35 to the inlet chamber 36 of the condenser 6. Cooling water then flows through the tubes 37 of the condenser 6 and is discharged from the system through a conduit 38.

The various elements of the refrigeration system are connected to each other to provide a closed hermetically sealed system which is initially evacuated to a very low pressure of at least 2 mm. Hg abs. or less. After the system has been evacuated a water solution of a salt such as lithium bromide is introduced into the system, the water of the solution constituting the refrigerant and the salt solution at different concentrations constituting the absorption solution weak in refrigerant and absorption solution strong in refrigerant. During operation of the system the generator 5 and condenser 6 may have a pressure of 40 mm. Hg abs. corresponding to a condensing temperature of 90° F. and the evaporator 7 and absorber 8 may have a pressure of 8 mm. Hg abs. corresponding to the vapor pressure of the lithium bromide solution at its particular temperature. The refrigerant, water, will then boil at 46° F. in evaporator 7 at the low pressure therein. In such a vacuum type system non-condensable gases are apt to occur which blanket the heat transfer surfaces of the condenser tubes 37 and cooling coils 31 of the absorber 7. These non-condensable gases probably result from corrosion in the unit and a large percent of the gases is hydrogen. While the corrosive effect on the elements of the unit may be negligible, the volume of hydrogen gas produced by such corrosion is excessive due to the low pressure and will interfere with the proper operation of the system.

To prevent the accumulation of such non-condensable gases in any element of the active part of the system means are provided for continuously transferring such gases from other parts of the system to one element thereof where they are collected and stored as described in detail in the Roswell reissue patent, referred to above. Suffice it to state herein that gases occurring in the generator 5 and condenser 6 are swept by the refrigerant vapor toward the outlet end of the condenser and pass through the orifice 19 concurrently with the liquid refrigerant into the evaporator 7. Non-condensable gases in the evaporator 7 and absorber 8 are swept by refrigerant vapor to the bottom and center of the absorber where turbulence is at a minimum. A purging device 39 is provided for withdrawing the gases from the absorber which is in the form of an auxiliary absorber having a chamber 40 connected to the main absorber by a suction tube 41 extending to the bottom and center of the latter where the non-condensable gases accumulate. A limited quantity of absorption solution weak in refrigerant flows from conduit 25 to the purge chamber 40 through a branch conduit 42 and flows over a cooling coil 43 in the chamber which is connected between the cooling water conduits 32 and 35. A fall tube pump 44 has its upper end extending into a cup 45 at the bottom of the purging device 39 and its lower end connected to a riser 46. The lower end of the riser 46 is connected to the conduit 26 for absorption solution strong in refrigerant flowing toward the generator 5 and the upper end of the riser is connected to a gas storage vessel 47. The gas storage vessel 47 is located above the highest level to which liquid

can rise in riser 46 at the pressures in the system. The gas storage vessel 47 also has a nipple 48 with a valve 49 for detachable connection to a vacuum pump 50 for evacuating the vessel of gases.

5 A concentration control vessel 51 of the type described and claimed in United States Letters Patent to Lowell McNeely 2,465,904 issued March 29, 1949, is provided for varying the concentration of the absorption solution in accordance with operating conditions. The side of the concentration control vessel 51 is connected to the end of the lowermost evaporator tube 20 by a conduit 52, the bottom of the vessel is connected to the inlet chamber 11 of generator 5 by a conduit 53 and the top of the vessel is connected to the header 22 by a vent conduit 54. Liquid refrigerant overflowing from the evaporator 7 is stored in the concentration control vessel 51 to increase the concentration of the absorption solution to correct the condition causing the refrigerant to overflow and the amount of refrigerant that can be stored varies with the height of the pressure balancing liquid column in the vessel.

20 In accordance with the present invention one of the elements of the refrigeration system has a wall of a material which is permeable to hydrogen and non-permeable to other fluids. Palladium is such a material through which hydrogen will diffuse from a source at a higher partial pressure to an atmosphere at lower partial pressure regardless of the total pressure at either side of the wall. For example, hydrogen will flow from a vacuum type refrigeration system of the type described from an extremely low absolute pressure of 8 mm. Hg abs. through a palladium wall to the surrounding atmosphere at 760 mm. Hg abs. so long as the partial pressure of hydrogen in the system is greater than the partial pressure of hydrogen in the ambient atmosphere. Such a palladium wall may be applied to any of the elements of the system where the gases are apt to accumulate such as the condenser or absorber but in the illustrated embodiment it is preferably applied to the gas storage vessel 25 to which the gases have been transferred from other parts of the system and are stored at a high concentration and partial pressure. The rate at which hydrogen gas will diffuse through a palladium wall is functionally related to its temperature and will diffuse through the material at atmospheric temperatures at a very slow rate. It is therefore desirable to heat the palladium wall to correlate the rate at which hydrogen will diffuse from the system to the atmosphere with the rate at which hydrogen is generated in the system.

30 In the illustrated embodiment of the invention the palladium wall is contained in a separate cell 55 connected to the gas storage vessel 47. As shown more clearly in the enlarged view of Fig. 2, the cell 55 is in the form of an upright chamber 56 connected to the gas storage vessel 47 adjacent its bottom by a conduit 57 and adjacent its top by a conduit 58. The palladium wall comprises a tube 59 of the material which extends vertically through the chamber 56 and is sealed thereto at opposite ends by means of silver solder 60 or the like. At one side of the chamber 56 and in intimate heat conducting relation with its wall is a well 61 containing an electric heating element 62. The electric heating element 62 is preferably connected to an electric control system for the refrigeration system, not shown, so that when the refrigeration system is in operation the heating element is energized but when the system is not in operation the heating element is de-energized. The higher the temperature of cell 55 the higher the rate of diffusion through the wall of the palladium tube 59 and the lower the temperature the lower the rate of diffusion and preferably the heating element is of such capacity relative to the cell 56 as to heat the palladium tube to a temperature between 300 to 500° F. Such heating of the cell 56 will cause a circulation of non-condensable gases from the gas storage vessel 47

through the conduit 57 upwardly through the chamber 56 of cell 55 and back through the conduit 58 to the gas storage vessel. Simultaneously, the heating of the cell 55 causes a flow of atmospheric air through the center of the palladium tube 59. Thus, the non-condensable gases are circulated through the cell 55 to maintain hydrogen at a higher concentration and partial pressure on one side of the tube wall and atmospheric air is circulated through the center of the tube to maintain air on the other side of the tube wall at a low hydrogen concentration and partial pressure so that hydrogen will diffuse through the wall 54 of the palladium tube 59 from the system to the atmosphere. One form of the invention having now been described in detail, the mode of operation of the complete system is described as follows.

Heat from steam supplied to the heating chamber 14 of generator 5 is transmitted through the walls of the generator tubes 10 to expel refrigerant vapor from absorption solution therein and lift the absorbent into the separating chamber 12. Refrigerant vapor flows at high velocity from the separating chamber 12 to the condenser 6 where the vapor is condensed to a liquid and the flow of refrigerant vapor carries any non-condensable gases to the outlet from the condenser. Liquefied refrigerant and non-condensable gases flow concurrently through the orifice 19 which is of such size as to permit such concurrent flow but maintain the difference in pressure between the condenser 6 and evaporator 7. Liquid refrigerant evaporates in the tubes 20 of the evaporator 7 at a low pressure and temperature to cool air flowing over the exterior of the finned tubes.

Simultaneously, absorption solution weak in refrigerant flows by gravity from the separating chamber 12 to the absorber 8 in a path of flow comprising conduit 23, outer passages 24 of the liquid heat exchanger 9 and conduit 25. Solution supplied to absorber 8 flows by gravity over the cooling coils 31 in the absorber 8 where it absorbs refrigerant vapor from the evaporator 7 to produce a low pressure and temperature in the latter. The flow of refrigerant vapor from the tubes 20 and through the headers 21 and 22 sweeps non-condensable gases toward the center and bottom of the absorber 8 where turbulence is at a minimum. Absorption solution strong in refrigerant flows by gravity from the bottom of the absorber 8 to the inlet chamber 11 of the generator 5 in a path of flow comprising the conduit 26, inner passages 27 of liquid heat exchanger 9, conduit 28, leveling chamber 29 and conduit 30. Any unevaporated liquid refrigerant flows from the lowermost tube of the evaporator 7 to the concentration control vessel 51 to vary the concentration of the absorption solution in accordance with operating conditions.

A portion of the absorption solution weak in refrigerant flowing toward the absorber 8 is diverted through the branch conduit 42 into the chamber 40 of the purge device 39 where it flows over the cooling coil 43. Such cooled absorption solution weak in refrigerant absorbs refrigerant vapor to produce a partial vacuum relative to main absorber 8 to draw in non-condensable gases through the suction tube 41. Such non-condensable gases are transferred by the fall tube pump 44 and riser 46 from the active part of the system to the gas storage vessel 47 in an inactive part of the system. The non-condensable gases are thus collected and segregated in the gas storage vessel 47.

Simultaneously with the operation of the refrigeration system the heating element 62 is energized to heat the purging cell 55. Such heating of the cell causes a circulation of gases in the gas storage vessel 47 through the cell 55 and a flow of atmospheric air through the center of the palladium tube 59. Any hydrogen gas in the cell 55 at a higher partial pressure than the partial pressure of hydrogen in the atmosphere will diffuse through the wall of the palladium tube from the closed refrigeration sys-

tem to the atmosphere. As the wall surface of the palladium tube 59 and the rate of heating are correlated with the expected rate of hydrogen generation in the system, the gas storage vessel 47 is continuously and automatically purged of hydrogen as fast as it is generated.

It has been found that contact of certain substances such as lithium bromide used as an absorbent will contaminate or poison the palladium so as to prevent the diffusion of hydrogen therethrough. This poisoning effect of lithium bromide or other refrigerants or absorbents can be easily corrected by washing the substances from the surface of the palladium wall. However, it is difficult to so locate the palladium cell 55 as to prevent contamination by refrigerants or absorbents during transportation or to wash the surface of the palladium wall after it has been contaminated. In Fig. 3 a modified construction is illustrated which automatically closes the cell 55 from the refrigeration system when the latter is not in operation and opens the cell for communication with the system when the refrigeration system is in operation. The arrangement illustrated in Fig. 3 is substantially identical with that illustrated in Fig. 2 except that a bimetallic strip 65 is connected intermediate its ends to the wall of the cell chamber 56 between the inlet and outlet conduits 57 and 58. A valve element 66 is mounted on each end of the bimetallic strip 65 and the arrangement is such that the valves are pressed into engagement with ports at the ends of conduits 57 and 58 at normal temperatures. However, at a high temperature which will exist when the heating element 62 is energized, the bimetallic strip 65 will automatically flex to open the conduits 57 and 58 to permit the flow of gases from the gas storage vessel 47 through the chamber 56 of the cell 55.

It will now be observed that the present invention provides a device for continuously and automatically purging hydrogen from a closed refrigeration system to the atmosphere. It will further be observed that the present invention provides a palladium wall in one of the elements of the system through which hydrogen diffuses from a relatively high partial pressure in the system to a lower partial pressure in the ambient atmosphere. It will further be observed that the present invention provides a heated cell connected to one of the elements of the system and having a vertically arranged palladium tube extending therethrough. It will still further be observed that the present invention provides an automatic valve means for closing the purging cell from communication with the refrigeration system when the latter is not in operation and opening the cell for communication with the system when the refrigeration system is in operation.

While two embodiments of the invention are herein illustrated and described, it will be understood that further changes may be made in the construction and arrangement of elements without departing from the spirit or scope of the invention. Therefore, without limitation in this respect, the invention is defined by the following claims.

I claim:

1. In a closed vacuum type heat transfer apparatus having a plurality of elements and containing a solution of water in absorbent from which water vapor is expelled by the application of heat and in which hydrogen is apt to accumulate as a foreign body which interferes with the proper operation of the apparatus, a purging device for automatically removing hydrogen from the interior of the closed apparatus comprising a wall in an element of the apparatus where hydrogen accumulates which is permeable to hydrogen and non-permeable to water vapor, said hydrogen automatically diffusing through said wall from the interior to the exterior of the apparatus, and the exterior surface of said hydrogen permeable wall being so arranged as to facilitate the escape of dif-

fused hydrogen therefrom to maintain a lower partial pressure of hydrogen in the atmosphere at the outside of the wall than the partial pressure of hydrogen in the atmosphere at the inside of said wall.

2. A purging device for a closed heat transfer apparatus in accordance with claim 1 in which the hydrogen permeable wall is composed of palladium and located in a cell connected to an element of the apparatus from which it receives hydrogen, and means for heating the cell.

3. A purging device for a closed heat transfer apparatus in accordance with claim 1 in which means are provided for continuously transferring hydrogen from other parts of the apparatus to the element having the hydrogen permeable wall.

4. In combination with a closed refrigeration system having a plurality of elements and in which hydrogen is apt to accumulate, a cell for purging hydrogen from the system comprising a chamber connected at its top and bottom to one of the elements where the hydrogen accumulates, a palladium tube extending vertically through said chamber and sealed thereto, and means for heating the cell to cause a circulation of hydrogen from the system through the chamber and a circulation of air through the center of the tube.

5. In a vacuum type absorption refrigeration system utilizing water as a refrigerant and a salt solution as an absorbent, a gas storage vessel, means for continually transferring non-condensable gases from the other elements to the storage vessel, and a cell for automatically purging hydrogen from the system to the atmosphere comprising a chamber connected to the gas storage vessel and a palladium tube extending vertically through the chamber, and means for heating the cell, the hydrogen diffusing through the wall of the palladium tube from a higher partial pressure in the cell to a lower partial pressure in the atmosphere.

6. In a closed refrigeration apparatus in which hydrogen accumulates as a foreign body, a cell connected to the apparatus and having a palladium wall through which hydrogen diffuses from the interior of the apparatus to the atmosphere, valve means for opening the cell for communication with the interior of the apparatus during periods of operation and closing the cell from the interior of the apparatus when the system is not in operation, and means responsive to an operating condition of the refrigerating apparatus for opening the valve means.

7. In a closed refrigeration system in which hydrogen accumulates as a foreign body and interferes with the operation of the system, means for transferring hydrogen from other parts of the system to one of the elements thereof, a cell connected to the element where the hydrogen

is transferred, a palladium wall in the cell through which hydrogen diffuses to the atmosphere, valve means for opening and closing the connection between the system and the cell, means for heating the cell, and a movable actuator responsive to the heating means for opening the valve means when the cell is heated.

8. In combination with a closed refrigeration apparatus in which hydrogen is apt to accumulate, means for automatically purging hydrogen from the apparatus comprising a wall in the apparatus which is permeable to hydrogen and non permeable to other fluids, a construction providing a flue for directing ambient air over the exterior of the hydrogen permeable wall, and means for heating the flue to cause circulation of ambient air there-through to sweep hydrogen from the exterior surface of the hydrogen permeable wall whereby to cause hydrogen to diffuse through the wall from a higher partial pressure in the system to a lower partial pressure in the ambient atmosphere.

9. In a refrigerating apparatus containing a working fluid in which hydrogen is apt to accumulate as a foreign body, means for transferring hydrogen from other parts of the system to one of the elements thereof, a cell connected to the element where the hydrogen is transferred, a wall of the cell being composed of a material permeable to hydrogen and non-permeable to other fluids and through which hydrogen diffuses from the interior of the apparatus to the ambient atmosphere, said hydrogen permeable wall being subject to contamination by the working fluid in said apparatus, and means for protecting the hydrogen permeable wall from contact by working fluid in any tipped position of the apparatus during transit while permitting flow of hydrogen to the wall during operation of the apparatus.
